Harry E. Ingram, Inventor,
By his Attorney,
W. B. Hutchinson.

Patented Sept. 5, 1922.

UNITED STATES PATENT OFFICE.

HARRY E. INGRAM, OF BROOKLYN, NEW YORK.

BAG BOTTOM.

Application filed April 28, 1921. Serial No. 465,086.

To all whom it may concern:

Be it known that I, HARRY E. INGRAM, a citizen of the United States, and a resident of the borough of Brooklyn, county of 5 Kings, city and State of New York, have invented a new and useful Improvement in Bag Bottoms, of which the following is a full, clear, and exact description.

My invention relates to improvements in 10 bag bottoms, and more particularly to the construction of the bottom portion of a golf bag, though the invention can be applied to other bags or similar receptacles. In golf bags, however, in which the clubs are carried, it is customary to drop the clubs frequently into the bag, and the bottom is subjected to severe strain and wear. The object 15 of my invention is to produce a bottom structure for a bag of this sort which while not expensive, is extremely strong and durable, and can be easily made and secured in position. In carrying out my invention, the bag proper can be of any approved material or 20 design, and the bottom part constituting my invention, can be adapted and fastened securely thereto. My invention is preferably 25 formed of metal, though this is not absolutely essential, and the bottom proper can be stamped or otherwise formed of one piece, 30 readily inserted in the lower part of the bag, and securely fastened, so that it cannot be displaced, and it will appear from the description which follows, that the bottom 35 part of the bag can, when made according to my invention, be a handsome structure.

Reference is to be had to the accompanying drawings forming a part of this specification, in which similar reference characters indicate corresponding parts in all the views.

40 Figure 1 is a sectional plan of a golf bag provided with my improved construction.

Figure 2 is a vertical section on the line 2-2 of Figure 1, and

45 Figure 3 is a broken detail side elevation of the lower part of the bag.

In the drawings I have shown my improved construction as applied to and forming the bottom part of a golf bag. The bag 50 can be of any suitable material and style, and I have shown it provided with the customary stay rods or braces 11, on the sides which are held between the sides of the bag and suitable keepers 12. The bottom 13 of the bag is preferably formed of metal which 55 is sufficiently ductile or malleable to be spun, pressed or stamped into shape, and is of the

same diameter and shape as the lower part of the bag in cross section, and is provided with a down-turned flange 15, which at the extremity is turned outward and upward as 60 at 15, to enclose the stiffening ring 16. This arrangement brings the bottom proper 13 well out of contact with the ground, and forms a stiff, firm structure. The ring 16 is a stiff strengthening ring, and is rigidly 65 held in the turned up part 15 of the bottom flange, in fact it is usually soldered, and makes the bottom very stiff at the bottom, while the top is raised out of contact with the earth, and this in connection with the 70 manner in which the bottom is riveted to the bag sides and stay rods, provides practically an indestructible bottom, that is one that will last longer than the rest of the bag.

The sides of the bag 10 tightly enclose the 75 flange 14 of the bottom, and fit against the top of the stiffening ring 16 as shown at 17 in Figure 2, and the upturned part 15 of the flange 14 fits snugly against the lower part 17 of the bag 10.

The lower portion of the bag and the flange 14 are fastened firmly together preferably by means of rivets 18 which are located preferably well up within the flange 14, and extend through the sides of the bag 85 and through the said flange, the rivets also extending through the keepers 12, if the bag is provided with keepers. The rivets are shown having the usual washers 19, and are headed on the inner side. This construction 90 makes a firm, strong, and inexpensive structure, and makes the bottom portion of the bag look well. It is particularly adapted to golf bags, because of the excessive wear on the bottom of such bags, but the principle 95 can be carried out in other forms of bags having non-metallic sides if desired.

Where the stay rods 11 are used they can be flattened at their lower extremities as shown in Figure 2, and the rivets 18 extend 100 through the flattened parts of the stay rods as well as through the other parts of the bag. This makes the bag bottom exceedingly rigid and strong.

105 I claim:—

As an improved article of manufacture, a bag having a non-metallic body portion entirely closed on the sides and with longitudinal stay rods spaced apart and extending substantially to the bottom of the bag, a 110 one-piece metallic bottom entering the lower end of the bag body and fitting snugly there-

in so as to form a raised closure of the lower end, the said bottom having an integral downturned flange forming its sides and its lower edge being turned up to engage the 5 lower edge of the body, a stiffening ring enclosed in the turned up part of the bottom flange and disposed so that the lower edge of the body will come substantially into con-

tact with the ring, and fastening devices extending through the flange of the bottom 10 and through the body and stay rods.

HARRY E. INGRAM.
